HEATING STOVE

Norman R. Cole, Central Building, and Philip A. Duryee,
1115 41st E., both of Seattle, Wash.

Filed Jan. 21, 1965, Ser. No. 83,506

Term of patent 14 years

(Cl. D81—10)

FIG. 3

FIG. 1 is a front elevational view of a heating stove embodying the design of the present invention,

FIG. 2 is a top plan view of the stove,

FIG. 3 is a side elevational view of the stove, both sides appearing the same, and

FIG. 4 is a front perspective view of the stove.

We claim:

The ornamental design for a heating stove, as shown.
